DANIEL G. TERRELL, OF WAKEFIELD, PENNSYLVANIA.

Letters Patent No. 79,281, dated June 23, 1868.

IMPROVEMENT IN BRAKE FOR HORSE-POWER MACHINE.

The Schedule referred to in these Letters Patent and making part of the same.

TO ALL WHOM IT MAY CONCERN:

Be it known that I, DANIEL G. TERRELL, of the town of Wakefield, in the county of Lancaster, and State of Pennsylvania, have invented a new and useful Improvement in Brakes for Horse-Power Machines; and I do hereby declare the following to be a full, clear, and exact description of the same, reference being had to the drawing accompanying this specification, and forming a part of the same, and to the figures and letters thereon, in which—

Figure 1 represents a side elevation of my invention, showing the same in two positions.

My invention relates to an improvement in brakes for horse-power and other machines, by means of which the brake is caused to act on the driving-wheel, when any accident may happen to the belt or any part of the machinery independently of the attendant.

It is well known to those who use endless-chain horse-power machines for threshing or other purposes, that, when a belt is broken or slips off, as is sometimes the case, or when some part of the machinery breaks, great danger arises at once, from the fact that the power of the horses being suddenly expended simply to turn the driving-wheel, causing a very rapid revolution of the same, finally throws the horses down and seriously injures them, or often destroys the machine, and endangers the lives of all who are near.

To remedy this, by supplying a brake which works automatically, in case of the slipping off of the belt, or breaking of the same, or breaking of any part of the machine, which loosens the belt so much that it slips around the pulleys without driving the machine, and at the same time have the brake capable of being used as an ordinary brake, to be worked by the attendant, whenever it is desired to lessen the speed of the driving-wheel, is the object of my invention.

In order that others may understand the construction and operation of my invention, I will proceed to particularly describe it.

A A represent the framework of an ordinary horse-power machine, having the driving-wheel, B, attached to it in the usual manner, motion being communicated to the thresher or other machine by a belt, C. The drawing shows the belt C as passing around drums at the end of the horse-power. The brake D is attached to near the pivoted end of the lever E, and is fitted to the convexity of the wheel, so that, when bearing upon it, the whole inner surface shall be in contact with it. The lever E, which is of wood, of proper size and strength, is pivoted at F, quite near to the circumference of the wheel, while the long and free arm extends backward, as shown. On the upper edge of the lever, at G, is a piece secured, which serves as a catch, by means of which it is held up, so that the brake will not act on the driving-wheel when the machine is in motion. This catch rests upon the latch H of the arm I, said arm being pivoted at J, on which it is free to turn. It is made of the form shown, and extends upwards and backwards above the belt C, between it and the frame, and carries, near its end, the drum K. This drum K is made wide enough to run upon the upper surface of the belt, and serves, by its weight, to keep the belt tight upon its pulleys. Being carried on the upper end of the arm I, and made of considerable weight, it rests upon the belt C all the while, and on the belt being removed by accident, such as breaking or slipping off a pulley or wheel, it instantly falls down, liberates the catch of the brake-lever from the latch H, and brings the upper end of the arm I against the upper part of the catch G, thereby pressing the same down with considerable force, and causing the brake D to act strongly upon the wheel, and stops its revolution almost instantly.

The lever E being very long, and the brake D attached so near its fulcrum, together with the weight of the drum K, renders the stopping of the driving-wheel certain, and almost instantaneous in the case of any accident happening, while the drum K is used beneficially at all times to keep the tension of the belt equable, so that there is no loss of power from the belt slipping on the wheel or pulleys. At the same time the lever E may be used as a hand-brake at any time desired, by simply bringing it to one side of the latch H, and pressing down its free end, when the brake D will be brought against the periphery of the wheel. When not in use it should be raised up and retained by the latch H, so as to be always in readiness (in case of accident) for use, by means of the weighted drum K.

There being but few parts, there is no liability to get out of order. It is very simple in its construction, easily made, and applied to horse-powers of any form. It is automatic in its action, and at the same time has nothing to interfere with its being worked by the attendant precisely as an ordinary brake, while it affords an effectual guard against any accidents that may happen to the machine or any of its parts.

Having thus described my invention, its construction, and mode of operation, what I claim as new, is—

The arrangement, in horse-powers, of the mechanism herein described, whereby the brake will be self-acting when the belt breaks or flies off, and also serves the purpose of a hand-brake, to stop the machine when the belt is on in running order, substantially as and for the purposes herein set forth.

In testimony whereof, I hereunto subscribe my name in the presence of—

DANIEL G. TERRELL.
